PUMP

Elek Benedek, Mount Gilead, Ohio

Application November 28, 1932, Serial No. 644,675

12 Claims. (Cl. 103—161)

This invention relates to improvements in pumps and motors of the variable delivery, rotary, multi-piston type and has for primary object the provision of a novel simplified structure which is able to carry substantially greater specific loads than pumps of conventional design and which is more efficient in operation.

Pumps of the conventional type include ordinarily an adjustable reaction member which operates with the pistons and which supports the hydraulic piston load on its supported ends through bearings which are disposed on either side of the pistons at a substantial axial span so that said reaction member is loaded as a both-15 end supported beam is loaded at its center by a concentrated load. In such pumps the enormous hydraulic load deflects the reaction member, which is ordinarily a drum, during each revolution in the direction of the resultant piston load 20 and causes periodic vibrations with a frequency proportional to the number of deflections per minute in the drum. This phenomena is further amplified by the harmonic swinging character of the resultant piston load, the plane of vibration of which is normal to the main deflection vibration of the drum. Such elastic deflections may be very minute in their magnitude; however, owing to the high speed of such pumps and the plurality of working pistons, their vibration may 25 reach the frequency of sound vibrations which results in considerable noise and the destruction of the liquid-tight fits between pistons and cylinders and cylinder-barrel and pintle respectively. Such vibrations of the reaction member are similar in character to the vibration of an elastic stressed wire which is kept in elastic vibration by periodic external forces.

Further characteristics of pumps of the conventional type are in the construction of their 40 piston assemblies, wherein the load transmitting means between piston and crosshead is a small elastic gudgeon pin, supported at its ends similarly to the drum support. Under the enormous piston load, the small gudgeon pins will deflect 45 and vibrate with the periodic piston load between suction and pressure periods and will cause a high frequency roaring noise in the pump and the connected pressure system, accompanied by considerable pressure fluctuation. The elastic vibrations of the cooperative active and passive 50 load transmitting bearing members causes cavitation and overcompression in the pressure fluid and the pump will operate with fluctuating pressure due to gases and non-homogeneous pressure

medium in the system, causing trouble in the connected hydraulic working circuit.

The main purpose of this invention is to provide a high pressure fluid pressure machine which operates with solid, non-fluctuating pressure fluid for novel industrial purposes such as required in steering gears of ships, in the catapults of airplane carriers, in the hangars of airships, and which has a useful life which makes the application commercial for novel industrial purposes at greater efficiency than heretofore and with the required factor of safety. The above aims and purposes are accomplished by a novel simplified pump construction in combination with the application of a new machine element, capillary 15 needle bearing equipment, which is fully described in my co-pending application, Serial No. 641,186, filed Nov. 4, 1932.

In order to describe more specifically the substance of this invention and make it more readily understood by those versed in this art, reference is made to the accompanying drawings forming a part of my claims and specifications, wherein:

Fig. 1 is a longitudinal sectional view of a pump constructed in accordance with the present invention, taken through the central valve of the pump.

Fig. 2 is an enlarged detail portion of the reaction member in Fig. 1.

Fig. 3 is the partial sectional elevation of a piston and its novel crosshead.

Fig. 4 is an enlarged detail section of a new bearing provided to transmit the combined radial and axial load of the cylinder barrel.

Fig. 5 is a partial sectional side elevation of a crosshead structure provided to engage the piston with the reaction member.

Fig. 6 is a normal section of the crosshead in Fig. 5, taken through one of the coupling elements of the structure.

Fig. 6—A is a slight modification of Fig. 6 showing the novel U-shaped structure of the crosshead unit taken through coupling bar 18 in Fig. 11.

Fig. 6—B is a normal sectional view of the crosshead structure taken through the centerline of the piston in Fig. 11.

Fig. 7 is a transverse sectional view of the pump constructed in accordance with the present invention taken through the centerline of all 50 pistons.

Figure 8 is a slight modification of Figure 3, showing the application of the new needle bearing element in the piston crossheads in case of larger pump units.

Figure 9 is a normal section of Figure 8 showing the novel combination of the piston and its associated circular crosshead structure.

Figure 10 is a slight modification of Figure 7, 5 showing the reaction member in its extreme eccentric position and the piston gudgeon pins packed with the new bearing needle elements.

Figure 11 is a normal section of a piston assembly taken through its plane of longitudinal 10 symmetry.

Referring to the drawings, 1 designates the drive shaft of the pump which is connected to a suitable source of driving power. Axially aligned with the shaft 1 and adjacent to it is the stationary cylindrical central valve 2 which cooperates with a rotary cylinder barrel 3 having a plurality of radially disposed individual cylinders 3¹¹ bored in its disc portion 3¹. The barrel has a larger tapered cylindrical bore as at 3¹¹¹ which cooperates with the tapered cylindrical valve 2 and adjacent to that it has a smaller cylindrical bore as at 3^{1V} in which the enlarged portion 1¹ of shaft 1 is pressed in against cooperative shoulders 1¹¹ and 3^V of the shaft and barrel respectively. 25 The shaft and drum are keyed together by key 38 and are secured rigidly against tangential and axial displacements by lock nut 37.

A plurality of radial pistons 4 is arranged to operate in radial bores 3¹¹. Each piston 4 is provided with a load-transmitting shoulder 4¹ and a suction operating threaded portion 4¹¹ which both cooperate with a gudgeon pin 5 with the particular purpose in view, that the enormous pressure will be transmitted through and by the 35 shoulder 4¹ whereas the much smaller suction work will be taken up by the threaded reduced portion 4¹¹ of the piston 4, see Figure 3.

Each gudgeon pin 5 is rockably mounted in the crosshead and is supported throughout its entire length in a structure comprising a circular prismatic segment which in the transverse section has a rigid U or H shape respectively. See Figures 5, 6, 6—A and 6—B. Within the U or H channel sections 6¹ and 7 is an integral element 45 6 or 6¹¹ respectively which is bored to receive and engage gudgeon pin 5. It will be noticed that the U or H shaped part of the circular structure is not bored through transversely as would be necessary if the segment were made from one 50 piece, but they are only rigidly secured to the gudgeon pin actuating members 6 and 6¹¹ respectively by coupling bolts 18 so that they have a certain required section modulus in the direction of the load transmission which is a very essential requirement for the efficient load transmission. This prevents fatigue and warpage of the U or H structure, and assures the free reciprocation of the segmental crosshead structure peripherally in its circular cooperating channel 55 formed by reaction members 8 and 9.

I have discovered that if the circular crosshead structures in which the gudgeon pins are engaged are bored throughout their entire widths, they deform, losing their circular shape 65 and consequently are unable to operate freely in their circular pathways, this being due to a weakened section resulting from the bore which produces the undesirable effects in operation referred to, even though the crossheads be otherwise of strong construction. To eliminate the 70 friction and the accompanying seizure of the crossheads in their circular pathways, formed by members 8 and 9 respectively, I provided the above described rigid circular structures of Figures 5, 6, 6—A, 6—B and Fig. 11 respectively.

The structure of the pathways for the several piston cross-head structures is also formed in a novel manner resulting in a rigid permanent U-shaped construction, the arrangement of the parts being such as to permit assembly of the pump in a novel and improved way. 5

Notably in present invention the reaction member proper 9, which encircles the cylinder and piston assemblies, is not split in the plane of the pistons as is customary in present routine designs of pumps but it is integral and has ground inner and outer plain cylindrical bearing surfaces in accordance with the substance of the present invention and for the purpose which will be described in the following specifications: 10

A pair of cheek plates 8—8 is rigidly assembled with an annular reaction member 9 by means of a plurality of axially disposed headless set screws 10. The cheek plates 8 are formed with inwardly extending flanges or circular ribs 8' 15 providing inner tracks for the cross-heads, the outer track being provided by the reaction member 9. The inner diameter of the member 9 is such that when the pistons, with cross-heads attached, are moved into their innermost positions in the respectively associated cylinders, the whole cylinder, piston and cross-head assembly may be moved relatively inside of the reaction member 9. 20

After the cylinder and piston assembly has been moved in member 9, the crossheads can be 25 radially pulled out so that cheek plates 8 and their circular rims 8' will coordinate the cross-heads with reaction member 9. Right after that is done powerful headless set screws engage 30 members 8 and 9 in one assembly forming a rigid centrally positioned circular path for the shoes or crossheads. It is evident that a radial shoulder not shown in the drawings may be provided for advantage between 8 and 9 so that they may 35 line up flush in the assembly. 40

The members 8 and 9, when thus secured together, provide a rigid reaction device formed with spaced outer and inner annular tracks, there being an outer track portion provided by the 45 member 9 and an inner track provided by the rim 8' of the cheek plate 8 on each side of a plane containing the axes of the cylinders. 50

The hydraulic piston load of the pistons is supported by a relatively fixed or stationary adjustable bearing shell 11, which surrounds the cylinders and pistons. Between the relatively rotating and relatively stationary reaction members 9 and 11 is a novel type of capillary needle bearing described in my co-pending application above referred to which comprises a plurality of slightly 55 contacting cylindrical needle-rollers 12 of about $\frac{1}{16}$ inch in diameter in the present instance and about 1 inch in length, separated in axial direction by a circular ring 13. The needle bearing elements 12, together with the intervening capillary oil bodies, transmit the thrust load between the relatively rotatable reactance element 9 and the relatively fixed reactance element 11, and distribute the load so as to provide for power transmission with low friction loss and also to provide for rapid conduction of heat from the inner reactance element 9 to the outer reactance element 11, thus promoting cooling of the entire machine. 60

Similar needles 14 are provided to transmit the 70 load of the crossheads 6 or 6¹ and 6¹¹ to the rotary reaction bearing member 9. Each piston thrust load is distributed over a substantially continuous area constituted conjointly by the needle bearing elements 14 and a plurality of intervening capil- 75

lary oil bodies. This arrangement provides for power transmission with low frictional loss, and moreover provides for rapid transfer of heat from the piston and crosshead outwardly to the 5 rotatable reactance element 9.

According to the substance of my present and above referred to inventions, the contacting roller-needles form a capillary oil-field between the bearing member races which, owing to the large 10 line contact needle bearing area and the capillary oil film between them permits individual rolling of the working needles, and floating for the idle needles at a specific bearing load as high as 15 10,000 pounds per square inch, which is ten times as great as is permissible in plain or anti-friction 20 bearings of conventional design. It is not necessary to further amplify the significance of such 25 bearings in high pressure pumps before those who are familiar with the problems of high pressure 30 and high speed pump designs in view of the fact that the bearing is the main limiting factor today 35 in variable delivery pumps in regard to higher pressure and higher efficiency. Today 3000 pounds is the maximum specific pressure which 40 can be applied continuously and without overheating in pumps of conventional design. Fortunately in most of the hydraulic applications 45 the maximum pressure is required only at peak pressure and for a few seconds, thus for a fractional part of the minute. In pumps of sub-normal 50 capacity with small size pistons, a higher specific pressure may be carried, however those cases are only exceptions and built on the intensifier principle. The normal capacity pump 55 is the one in which the piston diameter has a well established commercial ratio to the maximum stroke of the piston. In such pumps today it is difficult to secure the proper anti-friction 60 bearings which would fit into the desired and 65 available space and within commercial price.

The stroke-piston diameter ratio above referred to is slightly greater than unity and it ranges between one and two in present high pressure variable delivery pumps.

45 Needles 14 are packed in an H shaped retainer 50 15 so as to keep the needles in rolling or sliding parallelism as described in my application above referred to.

Each crosshead is provided with a pair of end 55 50 plates 16 on its ends to control the position of the individual needle bearings for the crossheads. Each plate 16 is secured to the circular structure 6 and 7 or to 6¹ and 6¹¹ by a plurality of machine screws 17 respectively.

55 Adjustable bearing ring 11 forms the relatively 60 stationary or passive race of my novel type of needle bearing, while reaction member 9 is the inner or active race of the bearing. The very small or capillary spaces between them taken up 65 by the needles 12 occupy but a very little radial dimension and thus the bearing means is formed practically from pump parts or it may be said that the complete needle bearing is formed by inner race 9, needles 12 and outer race 11, thus 70 65 the reaction member and the bearing for same make in assembly one complete needle bearing. One of them may be regarded as eliminated when compared with a present routine type of pump.

Figure 2 shows a double row needle bearing in 75 70 which needles 12 are separated by separator 13. In outer race 11 there is provision as at 11¹¹¹ to retain the needles against axial displacement in such a way that 11 forms circular shoulders 11¹¹¹ but still maintains an axial circular clearance as at 11⁴ so as to permit the capillary

interspaces of the needles and their races to draw in lubricant by capillary attraction from axial direction.

Similar provision is made for the crosshead needles 14, which are lubricated by the lubricant 5 maintained in the drum structure 8 and 9 from the slip passing the pistons by centrifugal force in a well-known manner. However, needles 14 which have a diameter between $\frac{1}{2}$ to $\frac{1}{4}$ inch 10 provide for the pistons under pressure a rolling flexible bearing structure, which under the combined action of centrifugal and capillary force lubrication, permit the needles to roll under the working crossheads around their individual axes with a theoretical friction coefficient of 0.004 15 instead of sliding with a coefficient of 0.10 to 0.01 under the most favorable sliding conditions. Under the sucking pistons above the dead centers of rods 19 and 20 in Fig. 10, the needles 14 are 20 naturally idle and they will float between two oil films with a floating sliding motion.

For larger units gudgeon pins 5 may also be 25 packed with needles as shown in Figs. 8, 9 and 10 in such a way that on the pressure side of the pins full length needles 28 and for the suction side shoulder needles 28¹ are provided. To facilitate the packing of needles into their capillary circular recesses, I usually fill the recess with heavy grease and then pack the needles therein. Preferably the gudgeons are mounted in the cross 30 heads between the outer and inner curved running surfaces of the latter which engage respectively with the outer and inner tracks on the reaction device 8-9.

To provide for the axial thrust of the tapered 35 cylinder and pintle assembly, I provided a novel type of capillary needle bearing to support the barrel 3 at its ends in which the needle rollers 21 are slightly taper ground as in Fig. 4 and mounted in complete bearing form between inner and outer bearing races 22 and 23; said races are hardened to a Brinnell of not less than 650 and made of high grade nickel alloy steel.

As shown, the rollers 21 are tapered and have 40 their axes inclined with respect to the pintle 45 axis, the smaller ends of the rollers 21 being closer to the pintle than the larger ends, and the smaller ends of each anti-friction bearing assembly facing towards the other anti-friction bearing assembly. By virtue of this arrangement, the bearings 21 effectively carry radial loads and axial loads in both directions and thus maintain the cylinder barrel in concentric relation to the 50 pintle.

The entire pump is enclosed in cylindrical casing 29 which is provided with load transmitting 55 sliding bearing pads 30 and 31 respectively, and with bosses 29¹ for the mounting of pump control equipment. The control equipment ordinarily cooperates with passive bearing race 11 and its 60 connecting means 11¹ with control rods 19 and 20 respectively.

Sliding bearing pads 30 and 31 cooperate with 65 similar complementary pads 11¹¹ provided in bearing ring 11. Pump body 29 is axially closed by end covers 34 and 35 respectively, in which tapered needle bearings 21 are mounted to support the cylinder barrel 3 and one of the pintle 70 end covers 34 is provided for inlet and exhaust connections as at 27 and 27¹ respectively. 27¹ 75 is diametrically opposite to 27 on the enlarged portion 21 of the pintle 2 and cooperates with coincident passages provided in hub 34¹ of end cover 34 in a well known manner. Inlet and exhaust passages 27 and 27¹ are in communication 75

with pintle passages 24, 24¹ and 25, 25¹ in a well known manner which further communicate with main pump ports 26 and 26¹ which are reversible and at different times each one of them may be 5 pressure or suction port as well. Suction and pressure ports 26 and 26¹ further communicate with a sucking and delivery group of pistons respectively which are separated by a solid bridge portion 21¹. See Figure 10.

10 Pump body 29 is further provided with stop shoulders 36 in order to limit the maximum stroke of the pump and with an eye bolt 33 for lifting purposes—drain connection 32 is quite an essential feature of the casing. The slippage 15 fluid will be drained through this connection so that the rotary pump assembly will rotate freely in the drained casing. End covers 34 and 35 are further provided with stiffening flanges 34¹¹ and 35¹¹ in order to make the pump support rigid 20 and vibrationless.

Drive shaft 1 is rigidly secured to barrel 3 by key 38 and lock nut 37 and its projection through hub 35¹ is guarded against slip by packing ring 39.

The pump will operate in a well known manner. 25 For example, let arrow 40 show the rotation of the pump, and the rotary needle bearing be shifted by control rods 19 and 20 from its center position as shown in Figure 7 toward its right off-center position as shown in Figure 10. It is 30 evident then how during the upper half of each revolution the pistons are carried outward by the needle bearing which is forced to rotate with the driving cylinder barrel and will suck through port 26. The pistons during the lower half of 35 the revolution are forced inward by the needle bearing and consequently will compress the fluid through port 26¹. When the needle bearing is in its on-center position with the cylinder body, the relative position of the plungers in their cylinders remains unchanged during the revolution 40 and, although the pump is running it will not deliver any fluid. Figure 7 shows the pistons and the needle bearing in their on-center positions.

45 It can readily be seen that the distance the needle bearing is eccentric with regard to the cylinder body determines the amount of the stroke and hence, the volume of the discharge, and that the finest variation from zero to a maximum can be obtained without stopping the pump.

Novel detail operative features of the pump are as follows:

Central valve 2 is rigidly supported in hub 34¹ 55 of end cover 34 through a heavy press fit so that the position of the valve is entirely independent and concentric in regard to the position of the barrel and when, after careful assembly and lap fit one in the other the slight selective 60 clearance between them acts as a continuous capillary interspace and will draw in fluid to provide capillary lubrication which is not the case when the cylinder is supported directly or semi-directly in the valve as in pumps of the 65 prior art.

Side flanges 8 of the inner race of the needle bearing are reaching beyond the outer diameter of the cylinder disc inwardly to retain fluid during the operation of the pump by the centrifugal 70 force and seals the end of the cylinders to prevent air suction at all times. This is an essential feature for the successful operation of a pump.

Various changes may be made in the embodiment of the invention hereinabove specifically 75 described, without departing from or sacrificing

any of the advantages of the invention as defined in the appended claims.

I claim:

1. In a pump or motor the combination of a 5 pintle, a plurality of radial piston and cylinder assemblies surrounding said pintle, a complete needle bearing surrounding said assemblies, a crosshead associated with each assembly, a reciprocating thrust needle bearing between each crosshead and the inner race of said complete bearing to sustain the hydraulic load of the 10 pistons, said thrust needle bearing comprising a plurality of parallel, bodily reciprocating capillary elements and associated cage member for maintaining the needles in their bodily relation during reciprocation and means associated with said inner race to maintain said crossheads in 15 working relation with said thrust needle bearings and to retain pressure lubricant to seal the outer end of each cylinder bore against suction of air. 20

2. A pump assembly including a pintle member, a cylinder barrel mounted for rotation about said pintle and having a plurality of cylinders therein, valve means for said cylinders, a piston for each of said cylinders, a crosshead for each piston, each of said crossheads being substantially U-shaped in cross-section and having an insert therein, means for attaching said inserts to said crossheads, each of said inserts having a bore for the reception of a gudgeon, a stem on each of 25 said pistons, a gudgeon on each stem, said gudgeons being received in the bores of the inserts, and reaction means surrounding said cross-heads and having thrust-transmitting driving connection therewith. 30

3. A pump assembly including a pintle member, a cylinder barrel mounted for rotation about said pintle and having a plurality of cylinders therein, valve means for said cylinders, a piston for each of said cylinders, a crosshead for each piston, each of said crossheads being substantially U-shaped in cross-section and having an insert 35 therein, means for attaching said inserts to said crossheads, each of said inserts having a bore for the reception of a gudgeon, a stem on each of said pistons, a gudgeon on each of said stems, said gudgeons being received in the bores of the inserts, needle bearing anti-friction devices intermediate each of said gudgeons and walls of the 40 associated bores, and reaction means surrounding said crossheads and having thrust-transmitting driving connection therewith. 45

4. In a pump assembly, the combination of a 55 stationary pintle, a rotatable cylinder barrel mounted for rotation about said pintle and having a plurality of cylinders, a piston for each cylinder, duct means interconnecting said pintle with said cylinders and affording communication for the working fluid therebetween, a crosshead for each piston, piston actuating means disposed about said cylinder barrel and including reaction means having thrust-transmitting engagement with said crossheads for imparting a suction stroke and a pressure stroke to each piston during 60 each revolution, said crossheads each comprising a body portion having depending walls, an insert lying between the walls of each crosshead and being joined thereto, each of said inserts having a bore therein, the wall of which forms one 65 wall of a bearing chamber, a stem on each of said pistons, gudgeons each having an aperture for receiving said stems respectively, said gudgeons being adapted to lie in the bores in said inserts and forming the other walls of said bear- 70

75

ing chambers, and needle bearing members disposed in said chambers.

5. In a pump assembly, the combination of a stationary pintle, a rotatable cylinder barrel mounted for rotation about said pintle and having a plurality of cylinders, a piston for each cylinder, duct means interconnecting said pintle with said cylinders and affording communication for the working fluid therebetween, a crosshead for each 10 piston, piston actuating means disposed about said cylinder barrel and including reaction means having thrust-transmitting engagement with said crossheads for imparting a suction stroke and a pressure stroke to each piston during each revolution, said crossheads each comprising a body portion having depending walls, an insert lying between the walls of each crosshead body portion and being joined thereto, each of said inserts having a transverse bore the wall of which forms 15 one wall of a bearing chamber, a stem on each of said pistons, gudgeons each having an aperture for receiving one of said stems, each of said gudgeons being adapted for rocking movement in said bore of the associated insert, each of said 20 gudgeons forming the other wall of the associated bearing chamber, and capillary needle members comprising elongated body portions lying in said bearing chambers thus formed to supply and maintain an effective double oil film in said 25 chambers by capillary attraction.

6. In a pump assembly, the combination of a stationary pintle, a rotatable cylinder barrel having a plurality of cylinders, a piston for each cylinder, duct means interconnecting said pintle 30 with said cylinders and affording communication for the working fluid therebetween, a crosshead for each piston, piston actuating means disposed about said cylinder barrel and including reaction means having thrust-transmitting engagement 35 with said crossheads for imparting a suction stroke and a pressure stroke to each piston during each revolution, said crossheads comprising a body portion having depending walls, an insert lying between said walls and being joined thereto 40 at spaced points having a transverse bore therein, the wall of said bore forming one wall of a bearing chamber, a stem on said piston, a gudgeon having an aperture for receiving said stem, said gudgeon being adapted for rocking movement in 45 said bore of said insert in forming the other wall of said bearing chamber, and anti-friction devices disposed in said chamber, to supply and maintain an effective oil film in said chamber by capillary 50 attraction, the depending walls of said crossheads 55 preventing axial displacement in said gudgeon members and said anti-friction devices in a transverse direction.

7. In a pump assembly, the combination of a pintle, a rotatable cylinder barrel having a plurality of cylinders, a piston mounted for reciprocation in each cylinder, duct means interconnecting said pintle with said cylinders and affording communication for the working fluid therebetween, a reaction device surrounding said cylinder 60 barrel and being formed with spaced outer and inner annular tracks, there being an outer track portion and an inner track spaced therefrom on each side of a plane containing the axes of said cylinders, means for supporting said reaction device in a position eccentric with respect to said 65 pintle, a rigid cross head for each piston having outer and inner running surfaces curved to conform to said tracks and engaging said outer track portions and said inner tracks on both sides of 70 said plane, a bore in each cross head extending 75

parallel to the axis of said pintle and being located between the outer and inner running surfaces on said cross head, and a gudgeon connected to each piston and extending into the bore in the associated cross head whereby the pistons are pivotally connected to their respectively associated cross heads at points between the engagement of the cross heads with the outer and inner tracks on the reaction device. 5

8. In a pump assembly, the combination of a pintle, a rotatable cylinder barrel having a plurality of cylinders, a piston mounted for reciprocation in each cylinder, duct means interconnecting said pintle with said cylinders and affording communication for the working fluid therebetween, a reaction device surrounding said cylinder barrel and being formed with spaced outer and inner annular tracks, there being an outer track portion and an inner track spaced therefrom on each side of a plane containing the axes of said cylinders, means for supporting said reaction device in a position eccentric with respect to said pintle, a rigid cross head for each piston having outer and inner running surfaces curved to conform to said tracks and engaging said outer track portions and said inner tracks on both sides of said plane, a bore in each cross head extending parallel to the axis of said pintle and being located between the outer and inner running surfaces on said cross head, and a gudgeon secured to each piston and being received in the bore of the associated cross head, and anti-friction devices disposed between the gudgeon of each piston and the associated cross head bore to supply and maintain an oil film between the gudgeon and the bore wall by capillary attraction, whereby the pistons are pivotally connected to their respectively associated cross head at points between the engagement of the cross heads with the outer and inner tracks on the reaction device. 10 15 20 25 30 35 40

9. In a pump or motor, the combination of a plurality of rotatable radial piston and cylinder assemblies, each including a relatively reciprocable member having a thrust-transmitting surface; rotatable annular reaction means surrounding said assemblies and having thrust-transmitting surface portions associated respectively with the thrust-transmitting surfaces of said reciprocable members; and needle bearing equipment interposed between the thrust-transmitting surfaces of said reciprocable members and the associated thrust-transmitting surfaces of said reaction means, said needle bearing equipment comprising a plurality of parallel, closely contiguous, individually rolling elements of very small diameter, said elements being of such size and so closely positioned relatively to each other as to provide, conjointly with said associated thrust-transmitting surfaces, a plurality of capillary oil spaces containing bodies of oil, whereby the load on each of said reciprocable members is distributed over a substantially continuous area constituted by the needle bearing elements and the capillary oil bodies, the continuous load-transmitting area providing also for rapid transfer of heat by conduction from said reciprocable elements to said reaction means. 45 50 55 60 65

10. In a pump or motor, the combination of a plurality of rotatable radial piston and cylinder assemblies, each including a relatively reciprocable member having an arcuate thrust-transmitting surface; rotatable annular reaction means surrounding said assemblies and having arcuate thrust-transmitting surface portions associated respectively with the thrust-transmitting sur- 70 75

faces of said reciprocable members; and needle bearing equipment interposed between the thrust-transmitting surfaces of said reciprocable members and the associated thrust-transmitting surfaces of said reaction means, said needle bearing equipment comprising a plurality of parallel, closely contiguous, individually rolling elements of very small diameter, said elements being of such size and so closely positioned relatively to each other as to provide, conjointly with said associated thrust-transmitting surfaces, a plurality of capillary oil spaces containing bodies of oil, whereby the load on each of said reciprocable members is distributed over a substantially continuous area constituted by the needle bearing elements and the capillary oil bodies, the continuous load-transmitting area providing also for rapid transfer of heat by conduction from said reciprocable elements to said reaction means.

20 11. In a pump or motor, the combination of a plurality of rotatable radial piston and cylinder assemblies, one member of each assembly being reciprocable; a relatively fixed annular bearing element surrounding said assemblies; a relatively floating annular bearing element also surrounding said assemblies and disposed between the latter and said relatively fixed element; a needle bearing equipment interposed between said relatively fixed and said relatively floating elements, said equipment comprising a plurality of lubricated, closely contiguous cylindrical bearing elements of such size and being so closely positioned relatively to each other as to provide, conjointly with said relatively floating element and said relatively fixed element, a plurality of capillary oil spaces containing bodies of oil, whereby the load transmitted between said relatively fixed element and said relatively floating element is distributed over a substantially continuous area constituted by the needle bearing elements and the capillary

oil bodies, the continuous load-transmitting area providing also for rapid transfer of heat by conduction from said relatively floating element to said relatively fixed element; and a similar needle bearing equipment interposed between said relatively floating element and the reciprocable member of each piston and cylinder assembly.

12. In a pump or motor, the combination of a plurality of rotatable piston and cylinder assemblies, one element of each assembly being reciprocable relatively to the other element thereof; a relatively rotatable annular reactance element surrounding said assemblies; a relatively fixed annular reactance element surrounding said relatively rotatable reactance element; thrust-load-transmitting bearing means interposed between said relatively reciprocable elements and said relatively rotatable reactance element and being constructed to conduct heat efficiently from said relatively reciprocable elements to said relatively rotatable reactance element; and thrust-load-transmitting bearing means interposed between said two reactance elements and being constructed to conduct heat efficiently from said relatively rotatable reactance element to said relatively fixed reactance element, one of said bearing means comprising a plurality of lubricated, closely contiguous, elongated cylindrical needle bearing elements of such size and being so closely positioned relatively to each other as to provide, conjointly with the elements between which they are positioned, a plurality of capillary oil spaces containing bodies of oil, whereby the thrust load is distributed over a substantially continuous area constituted by the cylindrical needle bearing elements and the capillary oil bodies, the continuous load-transmitting area providing also for rapid transfer of heat by conduction.

ELEK BENEDEK.
